UNITED STATES PATENT OFFICE.

OSCAR SHARP, OF GRAYVILLE, ILLINOIS.

FEEDING DEVICE.

1,146,108.

Specification of Letters Patent. Patented July 13, 1915.

Application filed August 5, 1914. Serial No. 855,167.

To all whom it may concern:

Be it known that I, OSCAR SHARP, a citizen of the United States, residing at Grayville, in the county of White and State of Illinois, have invented certain new and useful Improvements in Feeding Devices, of which the following is a specification, reference being had to the accompanying drawings.

10 This invention relates to certain improvements in feeding devices and has relation more particularly to a device of this general character especially designed and adapted to be employed in connection with fodder; 15 and the object of the invention is to provide a device of this general character whereby the fodder is automatically maintained at the upper portion of the trough or manger and is held in such a way as to prevent the 20 stock from throwing such fodder promiscuously about.

The invention consists in the details of construction and in the combination and arrangement of the several parts of my improved feeding device whereby certain important advantages are attained and the device is rendered simpler, less expensive and otherwise more convenient and advantageous for use, all as will be hereinafter more 30 fully set forth.

The novel features of the invention will be carefully defined in the appended claims.

In order that my invention may be the better understood, I will now proceed to 35 describe the same with reference to the accompanying drawings, wherein—

Figure 1 is a view in side elevation of a feeding machine, with parts broken away, constructed in accordance with an embodiment of my invention; Fig. 2 is a top plan view of the device as illustrated in Fig. 1; Fig. 3 is a vertical sectional view taken transversely through an end of the device as herein disclosed; Fig. 4 is a longitudinal 40 vertical section taken through an end of the device at substantially the transverse center thereof; Fig. 5 is a view in elevation, detached, of the plate herein disclosed as included in the locking means for the grate member; Fig. 6 is a fragmentary view in elevation of one of the strap members herein set forth; and Fig. 7 is a fragmentary view, partly in section and partly in elevation, of 45 a portion of the grate member herein set forth.

As disclosed in the accompanying draw-

ings, 1—1 denote spaced substantially vertical members having their longitudinal margins provided with the inwardly directed flanges 2—2, to which are suitably secured the end marginal portions of the side walls 3—3 of the trough or manger proper, it being observed that the members 1—1 constitute the end walls of such trough or manger and also constitute a supporting means for the device.

The lower longitudinal margins of the side walls 3—3 are provided with the inwardly directed flanges 4 which serve to limit the downward movement of the bottom 5 of the trough or manger, the movement thereof in the opposite or upward direction being controlled by the plates 6 constituting the inner faces of the upper portions of the members 1, such plates 6 being provided with the forwardly directed flanges 7—7 adapted to interlock with the flanges 2—2 and be fixedly connected therewith through the medium of the locking members 8, the lower portions of such plates 6 being 80 provided with the extensions 9 depending between the side members 3 and terminating a predetermined distance below the upper longitudinal edges thereof.

The bottom 5 has its opposite extremities 85 projecting beyond the plates 6 and to each of such projected extremities, as indicated at 10, is secured the lower extremity of a retractable member 11, herein set forth as a coil spring, the opposite extremity of such 90 member being suitably connected, as at 12, to a cross pin 14 suitably directed through the adjacent member 1 and plate 6, such position being preferably at substantially the transverse center of such member 1 and 95 plate 6 and adjacent their upper extremities. As is believed to be self-evident, the retractable members 11 serve to maintain the bottom 5 normally at the limit of its upward movement.

Hingedly secured to the outer face of one of the side members 3 and in close proximity to the upper longitudinal edge thereof is the grate member 15 which is adapted to extend across or bridge the space between 100 the side members 3 and is maintained in operative position through the medium of suitable locking means coacting with the opposite side plate 3. As herein disclosed, the grate member 15 comprises the longitudinally disposed side bars 16 adapted to overlap the side members 3 when in applied po-

sition, such side bars being connected by the spaced transverse strips 17, preferably formed of strap metal and having their extremities flexed downwardly to overlie the 5 side bars 16, as indicated at 18, an intermediate strip 17 having an extremity suitably flexed to afford a locking eye 19 adapted to be projected, when the grate 15 is in applied position, between the locking eyes 10 20 afforded along the upper marginal portion of a plate 21 suitably secured to the side wall 3 opposite to the wall to which the grate member is hingedly connected. A suitable locking pin is adapted to be projected through the eyes 18 and 20 when alined, whereby it will be seen that the grate member 15 will be effectively held in operative position.

At substantially its center, the bottom 5 20 has suitable secured thereto an extremity of a flexible member 22 which is directed downwardly therefrom and passed around a guide pulley 23 operatively supported by the transverse strap member 24 connected to 25 the inwardly directed flanges 4 of the side walls and is then extended longitudinally of the device and around a second guide pulley 23^a operatively supported by a second strap 25 and positioned in close proximity to an 30 end member 1. The flexible member 22 is then directed upwardly and fixed to a shaft 26 operatively supported in the side walls 3 and having one extremity projected, such projected extremity, as indicated at 27, being squared in cross section, whereby it may be properly engaged by an operating member 28 whereby it will be readily perceived that upon requisite rotation of the shaft 26, the bottom 5 will be moved to its lowermost 40 position whereupon the grate member 15 will be thrown out of operative position so that the fodder, such as hay, may be readily deposited within the trough or manger. The grate member 15 will then be turned 45 and locked into operative position and it will be readily perceived that the action of the retractable members 11 upon the bottom 5 will clamp the fodder between such bottom 5 and grate member 15 whereby such 50 fodder will be held in such a manner as to reduce to a minimum the possibility of the stock throwing the fodder promiscuously about; and it will also be observed that as the fodder is consumed, the action of the 55 retractable members 11 upon the bottom 5 will maintain the fodder at the upper portion of the trough or manger whereby the stock are relieved of the necessity of reaching down therein and also assures substantially all of the fodder being consumed.

While the manger or trough is being filled, it is advantageous that the bottom 5 be locked against the action of the retractable members 11 and, as herein discussed, I accomplish this through the me-

dium of the pawl 29 pivotally connected to a flange 2 by one of the members 1, such pawl or dog being provided in its under longitudinal marginal portion with a notch or recess 30 adapted to receive the angular 70 portion 27 of the shaft 26 whereby such shaft will be maintained against rotation and whereby it will be readily perceived that the flexible member 22 will thus serve to hold the bottom 5 against upward movement under the influence of the members 11. 75

While the guide pulleys 23 and 23^a may be operatively mounted in their respective straps 24 and 25 as desired, I find it of advantage to have the intermediate portions 80 of such straps disposed, as indicated at 31, to afford a pocket substantially U-shaped in cross section, the supporting shaft 32 for each of such pulleys being journaled in the substantially parallel side walls of the 85 pocket.

In order that the bottom 5 may maintain a substantially horizontal position, irrespective of its vertical adjustment, I find it of advantage to provide the corners of such 90 bottom 5 with the upwardly disposed guide posts 33 adapted to contact with the inner faces of the adjacent members 1, as is believed to be clearly disclosed in the accompanying drawings. 95

From the foregoing description, it is thought to be obvious that a feeding device constructed in accordance with an embodiment of my invention is of an extremely simple and comparatively inexpensive nature and is particularly well adapted for use by reason of the convenience and facility with which it performs its functions, and it will also be obvious that my invention is susceptible of some change and modification 100 without material departure from the principles and spirit thereof and for this reason I do not wish to be understood as limiting myself to the precise arrangement and formation of the several parts herein shown in 105 carrying out my invention in practice. 110

I claim:

1. A device of the character described comprising end members, side walls secured to said end members, plates secured to the upper extremities of the end members and disposed in spaced relation thereto, the lower extremities of the plates projecting below the upper edges of the side walls to afford stop members, a movable bottom positioned between the side walls and the end members and projecting beyond the plates carried by the end members, a grate member bridging the space between the side walls, and means for automatically imparting movement to the bottom in a direction toward the grate. 115 120 125

2. A device of the character described comprising end members, side walls secured to said end members, plates secured to the 130

- upper extremities of the end members and disposed in spaced relation thereto, the lower extremities of the plates projecting below the upper edges of the side walls to afford stop members, a movable bottom positioned between the side walls and the end members and projecting beyond the plates carried by the end members, a grate member bridging the space between the side walls, and means for automatically imparting movement to the bottom in a direction toward the grate, said means being disposed within the spaces between the end members and the plates carried thereby.
- 15 3. A device of the character described comprising end members, side walls secured to said end members, plates secured to the upper extremities of the end members and disposed in spaced relation thereto, the lower extremities of the plates projecting below the upper edges of the side walls to afford stop members, a movable bottom positioned between the side walls and the end members and projecting beyond the plates carried by the end members, a grate member bridging the space between the side walls, means for automatically imparting movement to the bottom in a direction toward the grate, and guide posts projecting upwardly from the bottom and extending within the spaces between the end members and the plates and in contact with the end members.
- 20 4. A device of the character described comprising end members, side walls secured to said end members, a movable bottom positioned between the side walls and end members, a grate member bridging the space between the side walls, a shaft rotatably supported by the side walls adjacent an end member, straps operatively supported by the side walls below the movable bottom, guide pulleys rotatably supported by the straps, automatic means for imparting movement to the bottom toward the grate member, and a flexible member secured to the bottom directed around the guide pulleys and operatively engaged with the shaft whereby rotation of the shaft in one direction serves to impart movement to the bottom away from the grate member.
- 25 5. A device of the character described comprising a trough having a bottom capable of vertical movement, a grate disposed across the top of the trough, means for automatically imparting movement to the bottom in a direction toward the grate, means operable for imparting movement to the bottom in the opposite direction, and inwardly disposed flanges carried by the trough at a predetermined distance below the movable bottom for limiting the movement of the bottom away from the grate.
- 30 In testimony whereof I hereunto affix my signature in the presence of two witnesses.

OSCAR SHARP.
